DESIGN FOR A DRAWER PULL

Leo A. Jiranek, Grand Rapids, Mich.

Application November 26, 1934, Serial No. 54,160

Term of patent 7 years

To all whom it may concern:

Be it known that I, Leo A. Jiranek, a citizen of the United States, residing at 541 College Ave. S. E., Grand Rapids, in the county of Kent and State of Michigan, have invented a new, original, and ornamental Design for Drawer Pull, of which the following is a specification, reference being had to the accompanying drawing, forming a part thereof, in which:

Fig. 1 is a perspective view of a drawer pull, showing my new design;

Fig. 2 is a perspective view thereof with the

cord wrapping removed for convenience of illustration; and

Fig. 3 is a sectional view taken on the line 3—3 of Fig. 2.

The dominant feature of my design consists in the corded medial portion, the end portions being illustrated in dotted lines to indicate non-essential features of the design.

I claim:

The ornamental design for a drawer pull as shown and described.

LEO A. JIRANEK.
